UNITED STATES PATENT OFFICE.

CHARLES J. BAUMGARTNER, OF ERIN TOWNSHIP, MACOMB COUNTY, MICHIGAN.

FLUE-CLOSURE.

1,248,244.

Specification of Letters Patent. Patented Nov. 27, 1917.

Application filed February 23, 1917. Serial No. 150,401.

To all whom it may concern:

Be it known that I, CHARLES J. BAUMGARTNER, a citizen of the United States of America, residing at Erin township, in the 5 county of Macomb and State of Michigan, have invented certain new and useful Improvements in Flue-Closures, of which the following is a specification, reference being had therein to the accompanying drawings.

10 This invention relates to a flue closure, and the primary object of my invention is to provide a double closure that can be easily and quickly installed to prevent wind, soot or other elements from passing through 15 a flue or stovepipe hole when not in use.

Another object of my invention is to provide inner and outer closure members for the ends of a stovepipe hole or flue, and to connect the members so that both members 20 will be frictionally held in engagement with the faces of a wall having a flue or stovepipe hole therein.

A further object of my invention is to provide a simple, durable and inexpensive 25 flue closure wherein effective means are employed for holding the closure members, particularly when installing the same, and I attain this and the above objects by a mechanical construction that will be herein- 30 after specifically described and then claimed.

Reference will now be had to the drawing, wherein—

Figure 1 is a horizontal sectional view of a wall having a flue and provided with the 35 preferred form of closure;

Fig. 2 is a front elevation of the outer closure member;

Fig. 3 is a horizontal sectional view of a wall having a flue provided with a modified 40 form of closure;

Fig. 4 is a front elevation of an outer closure illustrating a modification of my invention, and

Fig. 5 is an elevation of the inner closure 45 member shown in Fig. 3.

The outer closure member comprises two semi-circular plates 1 and 2 with the straight edge of the plate 1 overlapping the straight edge of the plate 2, so as to form substantially a disk or circular plate. The inner faces of the plates 1 and 2 are connected by hinges 3 and 4 so that the plates 1 and 2 may be folded toward each other, and in this manner the outer closure member collapsed in order that it may be placed 50 through a stovepipe hole 5 in a wall 6,

opened in the chimney flue 7 and placed against the outer face of the wall 6, as best shown in Fig. 1. To facilitate placing this member in position and temporarily holding the same, the plates 1 and 2 have resilient clips 8 adapted to frictionally engage the walls of the stovepipe hole or opening 5.

The inner member is in the form of a circular plate or disk 9 adapted for engagement with the inner face of the wall 6 so as to seal the inner end of the hole or opening 5. The member 9 has an inwardly projecting central hook 10 and adapted to connect 60 this hook and the hinge 4 of the outer member is a coiled retractile spring 11. The end of the spring 11 is detachable relative to the hook 10 and said spring is of sufficient length to permit of the free end thereof being extended and easily placed in engagement with the hook 10, so that when it is released, the retractile force thereof will 65 positively hold the inner and outer members against the wall 6, causing the marginal edges of both members to positively seal 70 the ends of the hole or opening 5.

In Figs. 4 and 5 of the drawing, there is 75 illustrated a slight modification of my invention in connection with both of the closure members. The plates of the outer closure member are provided with semi-circular clips or retaining members 12 adapted for engagement with the walls of the hole or opening 5 and the inner member has 80 bowed resilient or spring members 13 adapted to properly center the inner member relative to the axis or center of the hole or opening 5.

The flue closure in its entirety can be 85 made of light and durable metal with the inner closure member finished to present a neat appearance, and while in the drawing there are illustrated the preferred embodiments of my invention, it is to be understood 90 that the structural elements are susceptible to such changes, in size, shape and manner of assemblage, as fall within the scope of the appended claims.

What I claim is:—

1. A flue closure adapted for sealing the inner and outer ends of a stovepipe hole, comprising inner and outer members, the outer member composed of two semi-circular plates foldable relative to each other 110 and when open of a greater diameter than the diameter of the stove pipe hole so as to

5 seal the marginal outer edges of the stovepipe hole, and a retractile spring connecting said inner and outer members and adapted for holding said members against the faces of a wall.

10 2. A flue closure adapted for closing the ends of a stovepipe hole in a wall, comprising inner and outer members, the outer member being composed of semi-circular overlapping plates hinged at their overlapping edges so that said plates may be folded toward each other and shifted through the stovepipe hole and opened to engage the

15 outer face of the wall, retaining members carried by said outer member and adapted to engage the walls of the stovepipe hole, and a retractile spring connected to a hinge of the outer member and adapted to be attached to the inner member.

20 In witness whereof I affix my signature in the presence of two witnesses.

CHARLES J. BAUMGARTNER.
